J. D. COMSTOCK

AUTOMOBILE TIRE TREAD

Filed June 11, 1923

INVENTOR

Jackson D. Comstock
By Baker MacLain,
ATTORNEYS

UNITED STATES PATENT OFFICE.

JACKSON D. COMSTOCK, OF CHESTER, WEST VIRGINIA.

DESIGN FOR AN AUTOMOBILE TIRE TREAD.

Application filed June 11, 1923. Serial No. 6,466. Term of patent 14 years.

To all whom it may concern:

Be it known that I, JACKSON D. COMSTOCK, a citizen of the United States, residing at Chester, in the county of Hancock and State of West Virginia, have invented a new, original, and ornamental Design for Automobile Tire Tread, of which the following is a specification, reference being had to the accompanying drawings, forming a part hereof.

The drawing is a perspective view of an automobile tire tread embodying my invention.

I claim:

The ornamental design for an automobile tire tread as shown.

JACKSON D. COMSTOCK.
